OR D 19,939

ORNAMENTATION OF GLASS.

No. 19,939.

Patented June 24, 1890.

UNITED STATES PATENT OFFICE.

WILLIAM LEE PILKINGTON, OF ST. HELEN'S, COUNTY OF LANCASTER, ENGLAND, ASSIGNOR TO PILKINGTON BROTHERS, OF SAME PLACE.

DESIGN FOR THE ORNAMENTATION OF GLASS.

SPECIFICATION forming part of Design No. 19,939, dated June 24, 1890.

Application filed May 31, 1890. Serial No. 353,857. Term of patent 14 years. Registered in England November 26, 1889, No. 139,101.

To all whom it may concern:

Be it known that I, WILLIAM LEE PILKINGTON, of St. Helen's, Lancashire, England, a subject of the Queen of Great Britain, have 5 invented and produced a new and original Design for the Ornamentation of Glass, of which the following is a specification, reference being had to the accompanying drawing, forming a part thereof.

10. The figure is a plan of a sheet of glass showing my design.

The leading feature of my design consists in a series of protuberances of varying areas or sizes in juxtaposition in irregular order or 15 succession, and having smooth rounded tops or apices and irregularly radial indentations or depressions on their sides, with the said indentations on adjacent protuberances running into, interlacing, and crossing each 20 other, together with similar protuberances having seamed or roughened tops or apices located adjacent to some of the smooth-topped protuberances, and having irregularly radial indentations or depressions on their sides 25 running into, interlacing with, and crossing the similar indentations on the sides of said adjacent smooth-topped protuberances.

At A are shown protuberances which have smooth tops B, and which are arranged in 30 juxtaposition and in irregular order or succession in series over and covering a face of the plate of glass illustrated in the drawing. Each said protuberance has on its sides irregularly radial indentations or depressions 35 C, which run into, interlace with, and cross the indentations on the adjacent protuberances A of the series thereof.

At D are shown protuberances which are similar to the protuberances A, except that they have seamed or roughened tops or apices 40 E, and these protuberances D are located adjacent to some of the protuberances A in the said series thereof, while the protuberances D have irregularly radial indentations or depressions F, which run into, interlace with, 45 and cross the similar indentations C on the sides of the adjacent smooth-topped protuberances A.

What I claim is—

The design for the ornamentation of glass 50 herein shown and described, the same comprising a series of protuberances of varying areas or sizes in juxtaposition in irregular order or succession, and having smooth round tops or apices and irregularly radial indentations or depressions on their sides, with the 55 said indentations on adjacent protuberances running into, interlacing with, and crossing each other, together with similar protuberances having seamed or roughened tops or apices located adjacent to some of the smooth-topped protuberances, and having irregularly 60 radial indentations or depressions on their sides running into, interlacing with, and crossing the similar indentations on the sides of 65 the adjacent smooth-topped protuberances, as set forth.

WM. LEE PILKINGTON.
